(57) **CLAIM**

The ornamental design for a computer display with transitional anatomical structure image, as shown and described.

DESCRIPTION

This disclosure, in general, relates to an anatomical representation within an electronic medical record system and, in a particular embodiment, relates to an anatomical representation as displayed on a computer display within an electronic medical record system.

FIG. 1 is a front view of a first image of an anatomical structure displayed as a portion of an interface within an electronic medical record system for a computer display;

FIG. 2 is a front view of a second image thereof;

FIG. 3 is a front view of a third image thereof;

FIG. 4 is a front view of a fourth image thereof; and,

FIG. 5 is a front view of a fifth image thereof.

The appearance of the moving image sequentially transitions between the images shown in FIGS. 1–5. The process or period in which an image transitions to another forms no part of the claimed design.

The broken line showing of a portion of a computer display is included for the purpose of illustrating environmental structure and forms no part of the claimed design.

In a particular embodiment, FIG. 1, FIG. 2, FIG. 3, FIG. 4, and FIG. 5 provide the aesthetics of motion and zoom when displayed in sequence. For example, as an interface within an electronic medical record system changes to display a second anatomical structure from a first anatomical structure, the interface can provide an aesthetic that includes motion and zoom of anatomical features. In the exemplary embodiment of FIGS. 1 to 5, the interface of the electronic medical record system can provide an aesthetic transition from a first anatomical structure, such as a hand, to a second anatomical structure forming a portion of the first anatomical structure, such as a finger.
